UNITED STATES PATENT OFFICE.

EZRA E. WITTER, OF MILFORD CENTRE, OHIO.

CORN-HARVESTER.

SPECIFICATION forming part of Letters Patent No. 470,609, dated March 8, 1892.

Application filed August 21, 1890. Serial No. 362,702. (No model.)

To all whom it may concern:

Be it known that I, EZRA E. WITTER, a citizen of the United States, residing at Milford Centre, in the county of Union and State of Ohio, have invented certain new and useful Improvements in Corn-Harvesters, of which the following is a specification.

My invention relates to corn-harvesters, and it especially relates to improvements upon the corn-harvester described and set forth in my pending application, Serial No. 302,786, filed March 11, 1889.

The object of my invention is to simplify the constructions heretofore used in corn-harvesters of this class.

My invention consists in the various constructions and combinations of parts herein-after described, and set forth in the claims.

In the accompanying drawings, Figure 1 is a plan of a machine embodying my invention. Fig. 2 is a partial sectional view of the same, showing the arrangement of the mechanism for driving the different operating parts. Fig. 3 is a vertical sectional elevation view of the same. Figs. 4 and 5 are detailed views, respectively, in elevation and partly in section, showing the arrangement of the raising and lowering mechanism. Fig. 6 is a detailed view in elevation of one of the endless-chain gathering devices. Figs. 7 and 8 are respectively side and rear elevations, partly in section, of a shock-forming frame in detail. Figs. 9 and 10 are sectional elevations of detailed portions of the binding apparatus and driving mechanism, also showing the devices for raising and lowering the same. Fig. 11 is a bottom plan of the shock-forming frame and its operating mechanism. Fig. 12 is a detail of the same, showing the gate-latch. Fig. 13 is a detail of a portion of the binder raising and lowering devices. Figs. 14 and 15 are details of the needle-arm, Fig. 15 showing the arrangement of the binding-cord and slack-producing device. Fig. 16 is a side elevation of the parts shown in Fig. 15. Fig. 17 is a detailed view of a portion of the cutting apparatus. Figs. 18 and 19 are respectively a cross-section and partial plan view of the table-leaves in the shock-forming frame. Figs. 20 and 21 are similar views of the shock-formers. Figs. 22, 23, and 24 are respectively a plan, elevation, and bottom plan of the table-leaf supports and

latch. Fig. 25 is a sectional detail of the supporting-frame for the table, showing the outer leaf-supporting latches. Figs. 26 and 27 are respectively an elevation and plan of the rear caster-wheel. Fig. 28 is a side elevation showing the tilting devices. Figs. 29 and 30 are a plan and elevation, respectively, of the binder-table bridge. Fig. 31 is an enlarged detail of the same. Figs. 32 and 33 are details of the table-operating pawls. Fig. 34 is a detail of one of the supporting-wheels.

Like parts are represented by similar letters of reference throughout the several views. 65

In the said drawings, A A represents the main frame of the machine, which is supported on a main driving-wheel A' and a smaller supporting-wheel A², preferably in line with the driving-wheel A'. 70

B is the shock-forming device, including the binder and mechanism for discharging the bound shock therefrom. This shock-forming device is hinged to the main frame through the medium of the hinged connections a, 75 which are adapted to turn on a connecting-rod a', which extends along the rear of the machine, and are also adapted to slide laterally along said rod to shift the position of the shock gathering and forming device to 80 different positions with reference to the main frame, A A, as more fully set forth in my previous application heretofore referred to.

The shock forming and discharging devices are supported on a caster-wheel A³, the supporting-arm b of which is connected to the frame of the device B at b' and provided at its other end with a sleeve b², which carries a bifurcated journal-support b³, in which the wheel A³ is journaled. By means of the pivoted arm b the caster-wheel A³ may be adjusted laterally with reference to the frame to which it is attached, as shown by dotted lines in Fig. 27, so as to equalize the weight thereon and thus balance the machine and 95 the supporting mechanism on the three carrying-wheels A', A², and A³.

As before stated, the machine and all the operating parts are supported on three carrying-wheels. It is desirable that means be 100 employed for raising and lowering the frame and the operating parts with reference to the wheels to adjust the height of cut. It is also desirable that the frame and operating parts

be supported yieldingly on the wheels in order to obviate the jar and strain incident to passing over rough ground, such as is generally found in the corn-field. I preferably accomplish this in the following manner, (see Figs. 3 to 5 for details:) The carrying-wheels A' and A² are supported in sliding frames A⁵ and A⁷. The sliding frame A⁵, in which the main driving and supporting wheel A' is journaled, is adapted to slide vertically on guide-rods c c', which are each connected at their lower ends to the main frame A A and at their upper ends to a beam or head-block A¹¹. Secured rigidly in the top of the frame A⁵ and projecting upwardly between the guide-bars c and c', so as to pass through the head-block A¹¹, is an adjusting-screw c². This adjusting-screw c² carries a spur-gear c³, the hub of which is bored and screw-threaded to correspond to the screw-shaft c². The hub of the spur-gear c³ is made of sufficient length to fit snugly against the sides of a movable frame A¹², which as the gear c³ is revolved in either direction is adapted to be carried up or down along the screw c². Extending from the adjustable frame A¹² and the head-block A¹¹, with the respective ends resting against each, is a heavy coil-spring A¹³. The supporting-rod c', which forms one of the supports for the head-block A¹¹ and connects the same with the main frame A A, is preferably formed U-shaped and extended partly across the main frame A A and projected upwardly, as shown in Fig. 3, so as to form a guide-rod for one side of the movable frame A⁷, which carries the smaller supporting-wheel A². The frame A⁷ is also provided with an adjusting-screw c⁵, movable frame A¹⁵, screw-threaded spur-gear c⁷, and spring A¹⁷, arranged in substantially the same manner as before described for the main driving-wheel A'. The head-block A²¹, against which the spring A¹⁷ rests, is secured rigidly to the guide-rod c' and also to a smaller guide-rod c¹¹, which connects said head-block to the main frame A A and forms a guide for the movable frame A⁷ on the opposite side of said frame from the guide-rod c'.

It will be seen that as thus described the weight of the main frame is supported upon the two wheels A' and A² through the medium of the springs A¹² and A¹⁷, while the spur-gears c³ and c⁷ furnish the means for raising and lowering said frame with reference to the carrying-wheels by revolving said gears upon their screw-threaded standards. To provide for moving these gears simultaneously and uniformly to produce a uniform adjustment of the frame in a vertical direction, I provide within the movable frames A¹² and A¹⁵ spur-pinions c¹² and c¹⁸, adapted to mesh with the gears c³ and c⁷, respectively. The hubs of these pinions are also made of sufficient length to fit snugly within the movable frames, in which they are supported, and are each provided with a spline or feather adapted to slide in a keyway in the revolving vertical shafts c¹⁵ and c¹⁷. These shafts are each sup-

ported in suitable bearings attached to the head-blocks and to the main frame, respectively. Means are provided for connecting the shafts, so as to cause them to rotate together and at the same rate of speed, preferably by the use of a horizontal shaft c²¹, connected at each end to the respective shafts c¹⁸ c¹⁷ by miter gears c²² c²³. A small horizontal crank-shaft c²⁵ is also provided in the head-block A¹¹ and connected to the vertical shaft c¹⁵ by miter-gears c²⁷. (See Figs. 4 and 5 for details.) By the construction thus described it will be seen that means are provided for readily adjusting the main frame and its operating mechanism with reference to the driving-wheels, while at the same time the said main frame and all the operating parts are supported yieldingly on said main frame. The crank-shaft c²⁵ is placed within convenient reach of the operator, so that means are at hand by which he may raise or lower the machine at any time, as desired.

The main frame and the operating parts are preferably constructed for operating upon two rows of corn at the same time, as described in my other previous application heretofore referred to. The rotary cutters C and C', arranged in the throats C² C³, do not differ materially from those described in said application. As the machine is drawn forward motion is imparted to the cutters C and C', which are brought in contact by the advancement of the machine with the stalks in the respective rows which enter the throats C³ and C³. A side cutter C⁵ is also preferably provided at the side of the main frame in advance of the horizontal cutters C C' in the manner described in said former application to sever the down stalks in the next row.

C⁷ and C¹¹ are elevator-chains arranged at the sides of the respective throats for elevating the down grain and carrying it to the revolving cutters. I also provide a third elevating-chain C¹², which receives motion from the shaft which drives the said cutters C⁵ and extends upwardly therefrom at an angle to assist in carrying up and straightening down stalks to cause them to enter the throat and be severed by the main cutters in the manner hereinafter more fully described. Each of the chains C⁷ C¹¹ C¹² passes over supporting-sprockets C⁹, C²¹, and C²² at the top of the machine, which sprockets are arranged at substantially the same vertical height. The supporting-sprocket C²² of the chain C¹², however, is arranged in front of the sprocket C²¹, which causes the outer chain C¹² to assume a different angle from the chain C¹¹ and elevate the stalks at this point more rapidly than by the chain C¹¹, while they are carried backwardly at the same speed. The stalks severed by the cutter C⁵, as well as down stalks, are thus straightened and directed into the throat C³.

Motion is imparted to the respective cutters in the following manner: A spur-pinion d engages with the main driving-gear D, formed integral with and rigidly connected

to the main driving-wheel A'. The spur-pinion d is secured on one end of a short horizontal shaft supported in a bearing in the movable frame A⁵ and connected to a vertical shaft d' through the agency of beveled gears d² d³, the beveled gear d³ being formed with the hub of sufficient length resting within an opening d⁵ in the main sliding frame A⁵, the said frame A⁵ being provided on each side of said opening with bearings d⁷ d⁸ for the vertical shaft d'. The gear d³ is adapted to transmit its motion to the shaft d' by the aid of a spline or feather, which operates in the keyway d¹¹, formed in said shaft, this construction being adapted to permit a free vertical movement of the gear d³ and the frame A⁵ on the vertical shaft d' to permit the proper adjustment of the main frame and the supporting-wheels, as before described. One of the rotating disks of the cutters C is secured to this shaft d' near the lower end thereof and revolves therewith. Located on the shaft d' and secured rigidly thereto at points above and below the gear d³ are sprocket-wheels d¹², each of which carries a toothed chain d¹³, which passes around similar sprocket-wheels on a vertical shaft d¹⁵, arranged at or near the platform or main frame A A. At or near the lower end of the shaft d¹⁵ is a spur-gear d¹⁷, which engages with a similar gear d²¹ on a shaft d²². This shaft d²² is also provided with sprocket-wheels d²³, preferably two in number, carrying chains d²⁵, which pass over similar sprocket-wheels secured on a vertical shaft d²⁷, which carries one of the cutting-disks of the cutters C', and thus imparts motion to said cutters. The vertical shaft d²² is extended below the platform and is provided with a sprocket-wheel, which carries a chain, which extends over, as indicated by dotted lines in Fig. 2, and drives a short vertical shaft d³¹. This shaft d³¹ is made of sufficient length to come slightly above the platform and carries a sprocket-wheel, which drives an endless chain d³², which in turn, through the agency of a proper sprocket-wheel, drives a vertical shaft d³³, which carries the other cutting-disks of the cutters C. The shaft d³³ is extended upwardly through bearings in the head-block A²¹ and is connected to a similar vertical shaft d³⁵ through the medium of a horizontal shaft d³⁷ and miter-gears d⁵¹ and d⁵². The shaft d³⁷ also carries a suitable sprocket-wheel to drive the gathering-chain C', as shown in Fig. 6.

It should be stated that the shafts d³³ and d³⁵ each carry cutting-disks forming a part of the cutters C and C'. They are each extended above the head-block A²¹ and each provided with a rotating picker or gatherer D' and D², provided with extending arms adapted to revolve above the cutters and gather the stalks as they are severed by the cutters or brought thereto by the elevating-chains and force them into contact with the endless chains d¹³, d²⁵, and d³².

The respective chains d²⁵ and d¹³ are provided with teeth or fingers and are revolved

in the proper direction to engage the stalks of corn as they are severed by the cutters C and C' and carry the same between the shafts d¹⁵ and d²². The corn is held in a vertical position in its passage from the cutters to this point by means of guide-wires d⁵³, any suitable number of which may be used to act in connection with the said chains to hold the corn in a vertical position and cause it to be engaged by the fingers or teeth on said chains. These rods or wires are preferably made with a certain amount of resilience, which will permit them to yield under an undue pressure of the corn, but will exert sufficient pressure upon said corn to cause it to always be properly engaged by the carrying-chains.

Extending from a suitable sprocket-wheel on the shaft d¹⁵ to a similar sprocket-wheel arranged on a shaft e on the shock-forming device is a drive-chain e'. This shaft e is arranged at an angle slightly out of the perpendicular to correspond to the shape of the shock-forming frame, which is made larger at the bottom than at the top to correspond to the natural shape of the shock to be formed thereby, as shown in Fig. 28. From the shaft e below the platform of the shock-forming device a chain passes to and drives a short vertical shaft e², which extends upwardly through the platform and carries a spur-gear e³, engaging with a similar spur-gear e⁵ on a vertical shaft e⁷. (See Figs. 2 and 9.) From the shaft e⁷ is extended a chain e¹¹, which passes over a suitable sprocket-wheel on said shaft and over a similar sprocket-wheel e¹², arranged on a vertical shaft e¹³, supported in suitable bearings in the shock forming and binding device slightly in the rear of the shaft d²². This chain e¹¹ is also armed with fingers or teeth and operates in connection with the guide wires or rods e¹⁵ to carry and guide the corn into the shock forming and binding receptacle. A guide-wire e⁵¹ is also preferably provided to assist in guiding the stalks into the shock-forming receptacle. The shafts e⁷ and e¹³ are also each provided with two pairs of cranks e²¹ and e²², on which are journaled reciprocating serrated carrying-bars e²³ and e²⁵. These bars are adapted to be reciprocated as the shafts are revolved by the action of the drive-chains before referred to. It will thus be seen that the corn delivered from the carrying-chains d¹³ and d²⁵ between the shafts d¹⁵ and d²² is engaged by the reciprocating serrated carrying-devices e²³ and e²⁵ and forwarded along the passage formed between the said reciprocating bars and the guides or rods e¹⁵.

To assist the passage from the chains d²⁵ d¹³ to the reciprocating carrying devices and from the main platform to the hinged platform of the shock-forming device, I provide a picking or gathering device D⁸, secured to the shaft d¹⁵ near the top and adapted to revolve above the carrying-chains and thus grasp and force the severed stalks between the said shafts d¹⁵ and d²² and discharge the

same in the passage formed between the guide-wires e^{15} and the reciprocating bars e^{23} e^{25} . The chain e' , which connects the shaft d^{15} with the shaft e , and the chain e^{11} , which connects the shaft e^{13} with the shaft e' , are preferably armed with teeth to assist the angular backward and stubbleward movement of the corn in its passage from the harvester proper to the shock former and binder, while at the same time they are adapted to communicate motion between the respective parts named, the guide rods or wires e^{15} being preferably made resilient or yielding to compensate for the varying quantities of stalks in said passage.

The shaft e is made in two parts connected by a coupling e^{26} , which is joined to the upper part of said shaft by a feather or spline operating in a keyway in a well-known manner to form an adjustable connection between the parts. The upper portion of the shaft e is bent to form crank-arms e^{27} and e^{31} , on which are journaled reciprocating packer-arms e^{32} and e^{33} , each journaled near its middle on one of said cranks and connected at its inner end to a stationary lug or projection e^{34} on the bearing e^{11} of the packer-shaft, which bearing is supported on the movable bearing or sleeve n^2 of the needle-arm shaft by a pivoted connecting-link e^{35} , which as the shaft e is revolved gives to said packer-arms a reciprocating oscillating movement, which causes them to engage the incoming stalks and carry them into the shock forming and binding receptacle proper in the manner hereinafter more fully described.

The shock-forming device B in its general construction does not differ materially from that described in my previous application referred to. A circular revolving table B' is adapted to revolve in an outer circular cone-shaped frame B^2 , having at the bottom an annular supporting-flange B^{11} , in which the table revolves. The inner circular revolving table B' is provided with a partition B^3 , against which the incoming stalks are packed, which causes the circular table to revolve within the outer frame, as set forth in said former application. The table B' is composed of a frame-work consisting of an open ring B^{12} and backwardly-extending frame-pieces B^{13} B^{14} , to which are attached hinge-bars for the leaves f f' f^2 f^3 , hinged together and to the frame-pieces by "hinge-bars" and provided with springs to return them to their normal position, as described and set forth in my previous application and as shown in Figs. 11, 18, and 19. The hinge-bars and outer rim of the table, together with the dividing-partition, form a skeleton frame, through which the stalks forming the shock pass when the leaves are released in the same manner as set forth in my prior application. The leaves are adapted to be normally held in position to support the incoming stalks which rest thereon. As the corn is forced against the partition B^3 the table

revolves, the stalks being arranged within the outer casing and about the formers f^5 f^7 , which parts are substantially the same in their arrangement and construction as set forth in my previous application.

The corn in its passage from the harvester to the binding and shock-forming receptacle is supported in the frame-work B^5 , forming a part of the shock-forming device B, and on which the outer casing or frame B^2 is supported. At the point where the corn leaves the frame B^5 and passes into the outer casing B^2 and onto the table B' , I provide a pivoted bridge or floor f^{11} , pivoted at f^{12} to the frame and adapted to reciprocate between the table B' and the frame B^5 . To guide the stalks properly into the receptacle and against the partition B^3 , I provide curved pivoted guide-arms f^{13} f^{15} , pivoted, respectively, at f^{11} to the outer casing at the top and bottom, said guide-arms being provided with small springs f^{21} , adapted to hold them in their normal positions, as indicated in full lines in Fig. 2 and in detail in Fig. 29. As the table is revolved by the incoming stalks the partition B^3 is brought against the curved arms f^{13} f^{15} and they are forced outwardly to the position indicated in dotted lines in Fig. 2 to permit the table to continue its revolution. The bridge f^{11} is connected to the lower guide-rod f^{18} in the manner hereinafter more fully described, and is also carried by the movement of said arm without the radius of the revolving partition B^3 . By this time the partition B^3 has reached the opening through which the corn enters the outer casing B^2 , and a further revolution of the table B' by the incoming stalks cannot be accomplished. At this point the binding mechanism is thrown into operation by a lug or projection g on the bottom of the revolving table, which comes against a trip-lever g' , arranged below said table.

The binding mechanism does not differ materially from those already in use for binding grain. It receives its motion from the shaft e by a sprocket-chain g^2 , which drives a sprocket-wheel g^3 on a shaft g^5 , which shaft g^5 is extended through the frame B^5 and carries a pinion g^7 , which drives the binding mechanism. The chain g^2 is armed with teeth or fingers and is extended from a shaft e over an idler g^{11} , arranged above the frame or platform B^5 and in close proximity to the shaft e^7 , thus forming a throat, through which the stalks are crowded by the action of the chain g^2 , which thus assists in crowding the stalks into the binding-receptacle and against the partition B^3 . The trip-lever g' is arranged in a well-known manner to cause the pinion g^7 to transmit motion through the intermediate gears g^{12} g^{13} and spur-gear g^{15} to the knotter-shaft g^{17} . An oscillating movement is transmitted from the spur-gear g^{17} to the needle-arm shaft g^{21} through the agency of the pitman connection g^{22} . (See Fig. 11.) As the shaft g^{21} is revolved the needle-arm h is carried across the opening through which the

corn enters the binding-receptacle, thus bringing the cord or wire into the knotter or twister, by means of which the shock is bound, the knotter or twister being located on the opposite side of the throat from the needle-arm in a well-known manner, so that the needle-arm shall deliver the wire or cord thereto, any of the well-known devices for this purpose being used.

10 It should be noted that the end of the cord or wire is held in a suitable holder connected with or in close proximity to the knotter or twister, which is on the opposite side from the needle-arm of the passage through which 15 the stalks enter the binding-receptacle, so that as the shock is formed by packing the stalks into said receptacle it is formed in a bight or loop in the cord or wire in a well-known manner.

20 It will be seen that when the binding mechanism is set into operation the incoming stalks are cut off from the table by the needle-arm, and the movement of said table ceases. It is desirable, however, to carry the 25 partition a certain distance before the shock is bound and then another distance before it is discharged, so that the partition B^3 may remain stationary during the time that the ends of the cord or wire are being united 30 and afterward be brought to its original position, thus completing the revolution of said table, in order that the leaves $f^1 f^2 f^3$, which form the top of the table, and those of the formers $f^5 f^7$ may be brought in line with the 35 forward advance of the machine. To provide for this movement, I provide two reciprocating pawls i and i' , pivoted to a rocking arm i^2 on the needle-shaft g^{21} . The shaft g^{21} , it will be understood, simply receives an oscillating motion from the spur-gear g^{15} , sufficient to carry the needle-arm to the proper position with reference to the tyer or twister. This oscillating movement causes the pawls i and i' to come alternately in contact with a 45 projection i^3 on the bottom of the table B^3 and thus carry said table to the end of its revolution. These pawls i and i' , being attached to the rocking arm i^2 on opposite sides of the shaft g^{21} , are moved in opposite directions as said arm is oscillated, the pawl i being adapted to engage with the projection i^3 and carry it in a forward direction to the limit of the stroke of said pawl, where it is stopped temporarily while the ends of the cord or 50 wire are being united. In the meantime the other pawl i' has been moved backwardly until it has passed the pawl i , the said pawls occupying the relative positions shown in dotted lines in Fig. 11. As the motion of the 55 shaft g^{21} is reversed after the ends of the wire or cord have been properly united the pawls are returned to their normal positions, the pawl i' engaging with the projection i^3 and completing the revolution of the table B^3 .

60 The needle-arm h is provided with an extended portion h' on the arc of a circle concentric with the shaft g^{21} . This extension h'

has the double function of shutting off the incoming stalks and of assisting in paying out the cord to pass around the fresh shock 70 as the same is being formed by the incoming stalks. The latter function is performed in the following manner: A pivoted catch h^2 in the end of said arm is adapted to engage with the cord, which passes through two stationary guiding-eyes $h^3 h^5$ on either side of the path of said arm. Near the limit of the backward movement of said arm are two stationary stop projections $h^7 h^{11}$. The pivoted catch h^2 has an extended projection h^{12} , 80 adapted as the arm is moved backward to come in contact with the stop projection h^7 , and thus be turned to the position indicated by dotted lines in Fig. 16, in which position the cord is released, and the loop thus formed 85 between the stationary guiding-eyes and the pivoted latch is allowed to pay out freely through the stationary eye h^5 and the opening in the needle-arm. As the arm starts forward again the extension h^{12} comes against the stop h^{11} and returns the same to its normal position to engage the cord on its backward stroke. It should be noted that the stop h^{11} is placed considerably above the other stop h^7 , so that on the backward movement the extended end h^{12} of the catch h^2 passes under the stop h^{11} and comes in contact with the stop h^7 , which forces the extended portion upwardly and the catch portion downwardly. The catch h^2 being in this position will be engaged by the stop h^{11} on its forward movement and returned to its former position. The end of the cord being held in the holder or gripper in the usual manner as the arm returns to its normal position, the cord or wire 105 will be drawn from the spool by the catch, as described, until the limit of the backward movement of said arm is reached, at which time it will be released, thus forming a loop or bight to pass around the shock as the stalks are packed into the binding-receptacle.

The arrangement for discharging the bound shock is essentially the same as in my previous application, though much simplified, the operating-ring described in said application being dispensed with. A gate B^7 forms the rear portion of the binding-receptacle. As the table reaches the limit of its revolution the gate B^7 is automatically unlocked by a lug or projection j on the spur-gear g^{15} coming in contact with a pivoted catch-lever j' on the outer frame of the shock-forming device, which engages with and holds said gate B^7 in its normal position. At the same time the leaves $f^1 f^2$ are disengaged by a stop projection k on the outer frame coming in contact with a sliding bolt k' , secured to the moving table and adapted to operate the spring-catches $k^2 k^3$, which extend outwardly and engage the free edges of the respective 125 leaves. These spring-catches are shown in detail in Figs. 22 to 24, and consist, essentially, of latches $k^5 k^6$, pivoted at k^7 and each provided with a projecting arm k^{11} , against

which the end of the push-rod k' is adapted to engage. Extended portions k^{12} on each of said latches are engaged by a spring k^{13} , said spring being preferably formed of a single piece of steel wire passing around suitable projecting lugs k^{15} , with their free ends resting against the projecting portions k^{12} of the latches, as shown in Figs. 22 and 24. It will be understood that a double latch device—such as shown in Figs. 22 and 24—is employed to hold the central leaves f' f^2 , which open from the center, the latch device being supported on the skeleton frame of the revolving table at the base of the partition B^3 , the side leaves f f^3 being held by single pivoted latches k^{16} , as shown in Figs. 8 and 25. These latches k^{17} are adapted to be operated by lugs k^{21} on the outer casing as the table is revolved, which forces them to the position indicated by dotted lines in Fig. 25, thus releasing said leaves, said lugs being arranged in different planes, so that the lugs will strike only the leaves desired. As the table reaches the limit of its revolution, the shock having been properly bound, all the parts are returned to their normal positions, the leaves open, the gate B^7 is unlocked, and the shock falls through the table, the leaves of the former being turned to the position shown in dotted lines in Fig. 20. The table, leaves, and other parts will thus readily free themselves from the shock as the machine advances. The discharge-arm Z , forming a part of the binding apparatus, is preferably geared to move at the same rate of speed as the machine travels and begins to act on the shock simultaneously with the unlocking of the gate and table-leaves and bears against the top of the shock and, moving therewith, supports the same until clear of the other parts of the machine, leaving the shock standing in position on the ground. As soon as the different parts of the table have cleared the shock the leaves and gate are returned to their normal positions by the springs, as illustrated in detail in Figs. 18 to 21, after which the device is again ready for another operation.

To provide for holding the pawls i and i' in their proper positions and guide them around the flange of the revolving table, I provide guide-wires v , secured at each end to the frame B^5 and adapted to pass through the respective pawls, which are formed with openings v therein, as shown in Figs. 32 and 33, adapted to travel along said wires. These guides or wires are formed with a certain degree of resilience, which permits the pawls to pass the projection v , but at the same time holds the said pawls in close proximity to the flange and guides them in their travel about the table, as before described.

As before described, the harvester proper is supported on springs, with means for raising and lowering the machine with reference to the carrying-wheels to regulate the height of cut. I also preferably provide a spring l above the bearing-support b^3 of the caster-

wheel a^3 . An adjusting-screw l^2 is provided for adjusting the tension of said spring.

To provide for raising and lowering the binding mechanism, and thus bind the shocks at different heights to correspond to the different lengths of stalks, I form the respective shafts g^{17} and g^{21} in two parts, the lower portion of each shaft being formed in the nature of a sleeve adapted to receive the upper portion, which slides longitudinally through the same, the parts being caused to revolve together by a spline or feather in the sleeve portion operating in a keyway in the movable portion. The needle-arm h and the tyer or knotted wheel m are secured to the movable portions of the shafts and are adapted to be supported by movable bearings m' m^2 , the top of which rest in contact with the bottom of the hub or wheel and arm, as shown in Figs. 9 and 10. The bearings m' m^2 are each provided with a projecting lug m^3 , through which passes a screw-threaded shaft m^5 . These shafts m^5 are connected together by a longitudinal shaft m^7 and miter-gears m^{11} , as shown in Fig. 13, the shaft m^7 being adapted to receive motion from an inclined shaft m^{12} , which extends from a position near the seat of the driver and is connected to the shaft m^7 by a universal joint m^{13} . By turning the shaft m^{12} in either direction the binding device is adapted to be raised and lowered, as desired.

To secure the complete revolution of the table B^3 , it is desirable that the shaft g^{21} receive a slightly-greater movement than that necessary to move the arm h backward and forward. To provide for this movement, I connect the arm h to the shaft g^{21} by a set-screw n , which passes through the hub of said arm and into a keyway on said shaft, the hub being provided with a slotted opening n' , which permits a limited movement of said shaft in either direction before motion is imparted to said arm.

In order to secure a sufficient length of surface for the bridge f^{11} and provide for removing the same as the shock-forming device is revolved to permit the shock to make its revolution, I construct the bridge with a secondary or auxiliary leaf f^{22} , secured rigidly on a vertical shaft or stud f^{23} , which passes through and thus forms a pivotal connection with the main bridge f^{11} . This stud f^{23} is provided with a crank-arm f^{25} , which is connected by a link f^{27} to the guide-arm f^{15} . As the shock-forming device is revolved the arms f^{18} and f^{15} are pushed back, as indicated in dotted lines, carrying the bridge f^{11} and the auxiliary bridge f^{22} back, as indicated in dotted lines, and without the radius of the revolving table or shock-forming device.

The tilting device is shown in Figs. 1, 2, and 28. A rigid beam R is bifurcated at the rear and embraces a projecting flange R' on the frame of the shock-forming device, to which it is connected by a suitable bolt or pin p , which passes through a slotted opening

p' in said flange. The forward end of the beam *R* is pierced to receive a guide-rod *R*² on the main frame. An operating-lever *R*³, pivoted at *p*², has a projecting arm *R*⁵, connected by a link *R*⁷ to the beam *R*. A movement of the lever *R*³ changes the angular position of the main frame with reference to the beam and shock forming device, and thus tilts the forward portion of the frame up or down, as desired. The slotted opening *p'* permits the necessary movement of the beam with reference to the shock-forming device when said shock-forming device is shifted on the main frame, as before described.

15 I preferably employ a series of guide-wires *s*¹ *s*² *s*³ *s*⁴ *s*⁵ *s*⁶ between the respective throats *C*² and *C*³, which preferably extend upwardly and backwardly at an angle to form guides for the incoming stalks to assist in directing 20 the said stalks into the respective throats in a vertical position.

Having thus described my invention, I claim—

1. The combination, with a main frame and a carrying-wheel having an independent sliding bearing adapted to rise and fall in said frame, a screw-threaded stud connected to said bearing, and auxiliary frames having a screw-threaded wheel on said stud, of a spring 30 between said auxiliary frames and said main frame, substantially as specified.

2. The combination, with the main frame and the carrying-wheels, each having independent sliding bearings adapted to rise and fall in said main frame, of screw-threaded studs on said bearings, auxiliary frames, each having screw-threaded wheels on said studs, springs between said auxiliary frames and said main frame, and a revolving shaft for 40 simultaneously revolving said screw-threaded wheels, substantially as specified.

3. The combination, with a harvester and a shock-forming device, of the reciprocating carrying-bars located in a passage between the harvester and shock-forming device and adapted to be operated against the incoming stalks to carry them along said passage and a driving-chain extended between the supporting-shafts for said carrying-bars and in 50 the same plane therewith, said chain being provided with projections or fingers, substantially as specified.

4. The combination, with the reciprocating serrated carrying-bars journaled at each end 55 on vertical crank-shafts, as described, of a driving-chain extended between said crank-shafts and conveying motion from one to the other, said driving-chain being provided with projections or fingers adapted to move in substantially the same plane with said serrated carrying-bars as to their forward movement, substantially as specified.

5. The combination, with the shock-forming device and a supporting-frame, of a movable bridge located between said supporting-frame and shock-forming device, substantially as specified.

6. The combination, with a shock-forming device having a table, as described, of a movable bridge pivoted to the supporting-frame 70 and adapted to project over said table and means for withdrawing said bridge as said table is revolved, substantially as specified.

7. The combination, with a revolving table and a carrying-frame, of a hinged bridge having two pivoted leaves, as described, a curved guiding-arm pivotally connected to said bridge, and a spring for moving said arm, substantially as specified. 75

8. The combination, with a pivoted bridge 80 having two pivoted leaves, of a crank-arm rigidly connected to one of said leaves and pivotally connected to the other and means connected with said crank-arm for moving said bridge, substantially as specified. 85

9. The combination, in a shock-forming device having a bottom or table formed of hinged leaves, as described, said shock-forming device being formed with a gate at the rear thereof, a fastening device for said gate, and 90 means for operating said fastening device to release said gate as the table is revolved, substantially as specified.

10. The combination, with a shock-forming device consisting of an outer frame and an inner revolving table, of means for feeding the incoming stalks to cause said table to revolve, a binding mechanism for securing the shock formed in said device, and pivoted pawls connected with said binding mechanism, said 100 pawls being pierced at their outer ends to receive yielding guide-rods to permit them to reciprocate in opposite directions and to guide them so as to contact with the revolving frame and complete the revolution thereof, substantially as specified. 105

11. The combination, with a revolving table and an outer frame and binding-arm, of a pivoted pawl connected to the operating mechanism of said binding-arm and adapted 110 to engage with said revolving table and spring-guides piercing said pawls and adapted to hold said pawls in position to cause them to reciprocate about said table, so as to engage the same, substantially as specified. 115

12. In a shock-forming device, the revolving table adapted to be revolved by the action of the packers against the incoming stalks of corn, a binder-arm arranged above said table and adapted to be operated to secure 120 the shock formed on said table, and reciprocating pawls adapted to engage with said table and complete the revolution thereof by the movement of said binding-arm, said binding-arm being so connected to the operating mechanism as to permit of a limited movement of said mechanism without moving said arm, substantially as specified. 125

13. In a shock-forming device the bottom of which consists of a revolving table having 130 hinged leaves, an outer stationary frame in which said table revolves, spring-catches adapted to hold said leaves in their normal position, and cam projections on said stationary

frame adapted to engage said spring-catches and thus release said leaves, substantially as specified.

14. The combination, with the hinged or folding leaves of a shock-forming table, of the spring-catches consisting of two pivoted leaves having outwardly-extending projections, a push-rod engaging said projections, and a spring formed of a single piece of metal bent around stationary projections and adapted to engage the respective leaves, substantially as specified.

15. The combination of a binder-arm having an extended portion provided with a pivoted latch in the extremity thereof, a supporting-frame having guides for the cord which passes to said binder-arm, said guides being arranged on either side of the path of said extended portion, and tip projections on 20 said frame to engage with said pivoted latch, substantially as specified.

16. In a binding mechanism, a cord-arm having the rear extended in the arc of a circle in which said arm travels, a pivoted latch 25 in the rear extremity of said extended portion, adapted as the arm is reciprocated to cross the path of the cord in its passage to the arm and engage said cord, and means at the limit of the stroke of said arm for operating said catch to release the cord, substantially as specified.

17. The combination, in a binding mechanism, of a cord-arm having the rear extension, as described, and a pivoted latch in said extension adapted to engage the cord on the 35

backward movement of said arm, and means at or near the limit of the backward stroke of said arm for releasing said cord, substantially as and for the purpose specified.

18. The combination, with the cord-arm having the rear extension and pivoted latch, said pivoted latch being adapted to engage the cord on the backward movement of said arm, of a stop projection for moving said latch to release the cord when said arm has arrived at 45 or near the limit of its backward stroke and means for returning the latch to its normal position as the arm is moved in the forward direction, substantially as specified.

19. The combination, with a cord-arm having the rear extension and pivoted latch, as described, of the cord-guides h^3 h^5 and stop projections h^7 h^{11} , substantially as specified.

20. The combination, with the revolving table and binding mechanism, of the automatic dumping devices connected with said table for releasing the shock formed thereon, and a discharging device connected with said binding mechanism and adapted to move at substantially the same rate of speed as the forward advance of said table, and means for operating said discharging device simultaneously with the discharge of the shock from said table, substantially as specified.

In testimony whereof I have hereunto set 65 my hand this 15th day of August, A. D. 1890.

EZRA E. WITTER.
